VIBRATING TABLE

Mack Rogers and John Rogers, Oakland, Calif.

Application October 19, 1937, Serial No. 169,864

2 Claims. (Cl. 128—71)

This invention relates to improvements in vibrating tables and has particular reference to a table upon which a person rests and is then given a treatment of a vibratory nature.

5 A further object is to produce a device of this character which is adjustable to persons of different lengths, a table which is comfortable, and one wherein the person thereon is stretched during the vibratory period.

10 A further object is to produce a device of this character which is economical to manufacture.

Other objects and advantages will be apparent during the course of the following description.

In the accompanying drawings forming a part 15 of this specification and in which like numerals are employed to designate like parts throughout the same.

Fig. 1 is a side elevation of our table;

Fig. 2 is a top plan view of Fig. 1;

20 Fig. 3 is a side elevation of the head rest and chin strap;

Fig. 4 is an end elevation partly in cross section of the ankle engaging members;

25 Fig. 5 is a longitudinal sectional view taken on the line 5—5 of Fig. 2; and

Fig. 6 is a fragmentary detailed view of the means for stretching the ankles and by which the same may be longitudinally adjusted.

There are many bodily ailments in which it has 30 been found beneficial to vibrate the body and to also stretch the body so as to increase the circulation in the pads between the vertebra.

Applicants have, therefore, devised a table 35 wherein persons of different lengths may readily be gently stretched, and at the same time, while so stretched, have their entire body vibrated so as to increase the circulation to produce a beneficial result.

In the accompanying drawings wherein for the 40 purpose of illustration is shown a preferred embodiment of our invention, the numeral 5 designates a cabin-like table upon which is supported by springs 6, a top 7. This top has placed thereon a series of pads 8 of any desired number, and 45 it is upon these pads that the patient lies. The head pad and foot pad are cut away so as to allow for adjustable head and foot sections 9 and 11 respectively. The head section 9 is provided with a pair of uprights 12, which are joined with a 50 chin strap 13. This head section is in turn carried on sliding bars 14 and has connected thereto a rod 16, (see Figs. 2 and 5) which rod enters a cylinder 17 and has a piston 18 connected thereto. The foot section 11 has a vertically adjustable 55 ankle engaging clamp, comprising a lower section

19 and an upper section 21. This upper section 21 is connected to a rod 22, extending through the lower section and having teeth 23, which are engaged by a spring pawl 24. This foot section is also mounted on sliding rods 26 and has a rod 27 5 which enters a cylinder 28 and has a piston 29 connected thereto. The cylinders 17 and 28 are connected by pipes 31 to a hydraulic pressure device, to be hereinafter mentioned. Suspended below the table top 7 is a bracket 32, upon which a 10 fly wheel 33 is mounted. This fly wheel has a counter-weight 34 and is driven by a belt 36 from a motor 37, mounted upon the cylinder 28. Some of the pads 8 are mounted upon vertically movable sections 38 to which are connected pistons 15 39, mounted in cylinders 41 secured to the top 7 of the table. Hydraulic or air means may serve to lift the pistons 39, as will be hereinafter described. Any means may be employed for holding the foot and head sections in adjusted position, as 20 for instance, a pivoted dog and ratchet arrangement, as shown in Fig. 6. At 42, we have shown adjustable arm engaging hooks, which are vertically and longitudinally adjustable, the purpose of which is obvious.

25 With the device constructed and assembled, as shown in the drawings, a patient lies upon the table with the hooks 42 engaging the arm pits and the head upon the head rest 9 and the strap 13 adjusted about the chin. The angles are now 30 placed through the loops formed by the lower and upper ankle members 19 and 21, after which the pistons 18 and 29 are actuated through the application of fluid pressure, with the result that the head section and the foot section are moved away 35 from each other, thus stretching to a slight degree the spine of the patient. Other valves are now opened so that the pistons 39 on the various pads will exert upward pressure so as to raise the pads to conform to the general contour of the body, 40 as shown in dotted lines in Fig. 1. The motor 37 is now started, with the result that the fly wheel and its counterweight 34 will start to revolve; and as the counterweight is off center, a vibration will be set up through the bracket 32 to the table top 45 7, mounted upon the springs 6. Therefore, the patient will have the entire body vibrated during the stretching period. The amount of pressure exerted in the stretching may be indicated on suitable dials, and a clock may also be provided for 50 accurately determining the length of the treatment.

55 It is to be understood that the form of our invention herewith shown and described is to be taken as a preferred example of the same and

that various changes relative to the material, size, shape and arrangement of parts may be resorted to without departing from the spirit of the invention or the scope of the subjoined claims.

- 5 Having thus described our invention, we claim:
1. In a device of the character described, a table, supporting springs mounted on said table, a table top mounted on said supporting springs, an adjustable head section and an adjustable foot section carried by said top, means for securing the head and ankles to said head and foot sections respectively, fluid pressure means for moving said head section and said foot section away from each other, and means for vibrating said table top comprising a motor driven counterweight capable of imparting vibratory action to said table top.
  - 10 2. In a device of the character described, a

table, supporting springs mounted on opposite ends of said table, a table top mounted on said supporting springs, an adjustable head section and an adjustable foot section carried by said top, means for securing the head and ankles to said head and foot sections respectively, fluid pressure means for moving said head section and said foot section away from each other, means for vibrating said table top, comprising a motor driven counterweight cooperatively associated therewith, and vertically adjustable pads carried on said top, said pads having fluid pressure cylinders associated therewith to move the same into engagement with the body of the patient thereon to conform to the general contour of the 15 body.
